CARBURETOR

George R. Ericson, St. Louis, Mo., assignor to
Carter Carburetor Corporation, St. Louis, Mo.,
a Corporation of Delaware

Application January 7, 1933. Serial No. 650,607

9 Claims. (Cl. 261—34)

This invention relates to carburetors and particularly to accelerating pumps for carburetors. In previous devices of this kind it has been customary to provide a main fuel supply device, capable of supplying the required ratio of fuel in proportion to the air which flows through the carburetor at all normal constant operating speeds. For purposes of acceleration, a pump was provided. This pump was ordinarily connected 10 to the throttle valve, or to a suction device controlled by the depression above the throttle, that is, the suction prevailing between the throttle valve and the intake manifold of the engine. These pumps ordinarily have inlet and outlet 15 valves, and operate upon an opening movement of the throttle to discharge a pre-determined quantity of fuel into the mixing conduit.

Such devices were subject to the objection that when the carburetor was operated at high speeds, 20 the current of air flowing through the mixing conduit set up a suction at the discharge nozzle of the accelerating pump, sufficient to cause a continuous discharge through the pump as long as the high speed was maintained. This resulted 25 in a waste of fuel, and undue enrichment of the mixture, because the main nozzle is already calibrated to give just the right amount of fuel. The condition cannot be corrected by merely adding spring pressure to hold the inlet or outlet valves 30 closed, for that would interfere with acceleration under certain conditions. It would not be convenient or practical to calibrate the main fuel supply device in such a manner as to give just the right amount of fuel for a wide open throttle 35 low speed operation and then to arrange to have this ratio suddenly cut down, just at the point where the pump nozzle begins to discharge by suction.

It is an object of this invention to provide a device of the above described character in which the pump nozzle will be prevented from discharging by suction at high speeds.

Other objects and advantages will appear from the following description and accompanying drawing, referring to which:

Figure 1 is a diagrammatic representation of a carburetor embodying my invention.

Figure 2 is a sectional view on a larger scale showing the air bleed valve and the associated parts.

Figure 3 is a view similar to Figure 2 except that the parts are in a different operating position.

Figure 4 is an end view of the plug which carries the air bleed valve and associated parts.

Figure 5 shows a slightly modified form of the device.

Referring to the drawing the reference numeral 1 indicates the mixing conduit of a downdraft carburetor of previously known construction. 20 This mixing conduit is provided with an air horn 2, a venturi 3, mixture discharge outlet 4, and flange 5 by means of which the carburetor is attached to the intake manifold of an internal combustion engine, a throttle valve 6 mounted on shaft 7 is provided.

The air horn 2 is provided with a choke valve 8, mounted on shaft 9, which shaft is adapted to be operated by an arm 10. A lost motion connection 11, connecting the throttle and choke valves, is 25 provided to insure an opening movement of the choke valve whenever the throttle is fully closed or fully opened, without preventing free operation of the choke when the throttle is in an intermediate position.

A float chamber 13 in which the fuel is maintained at a constant level A—A by a float 14 is mounted in conventional relation to the carburetor. Fuel is supplied to the constant level chamber by a conduit 15 controlled by valve 16 as 30 indicated, the conventional vent 17 is provided for the upper part of the float chamber. A rocker-arm 18 mounted on pivot 19 is connected with the throttle by means of link 20 and arm 21 which is fixed to the shaft 7. 35

The accelerating pump comprises a cylinder 22, having a piston 23 therein, which is connected to the rocker-arm 18 by means of a rod 24. The conventional inlet and outlet valves 25 and 26 respectively are provided for the pump cylinder, and 40 the outlet valve 26 discharges into a conduit 27, which is connected to nozzle 28, which nozzle discharges into the mixing conduit anterior to the venturi 3.

It will be understood, of course, that the venturi 45 3 is representative of a construction in which either one, two or three venturis may be provided, but it is desirable that the accelerating pump should discharge anterior to the point of highest restriction in the mixing conduit.

At the junction of the passages 27 and 28, which is indicated by the reference numeral 29, a valve retaining plug 30 is inserted in the body of the carburetor. This plug is attached by means of conventional screw threads 31 and is provided 50 with a screw driver slot 32, by means of which it may be applied or removed. A gasket 33 is provided to prevent leakage. The plug is provided at its lower end with a comparatively large bore 34, terminating in a shoulder which forms 55 110

a valve seat 35, and a small bore 36, which connects the bore 34 with a cross passage 37. The cross passage 37 terminates in annular recess 38, which communicates with return passageway 39 leading back to the constant level chamber.

The valve 40 is made of fibre or other very light material, preferably a fibre or other material which is floatable in gasoline. This valve is held in the bore 34 by means of the retaining member

10 41 which is firmly pressed into the bore, the retaining member is perforated as indicated so as not to interfere with the flow of air from passageway 39 into passageway 28, whenever the valve 40 is in its open position as indicated in

15 Figure 3. It will be noted that the valve 40 is mounted in a plane at an acute angle to the horizontal so that in operation when the valve and valve seat become wet with fuel, the fuel will be drained off down to the lower edge of the valve

20 and from there down the sides of the bore 34 so as to minimize the tendency of the valve to stick in closed position, being held there by the surface tension of the fuel.

It may be noted that the main source of fuel

25 supply comprises nozzle 42, and idle port 43 which are supplied with fuel from the constant level chamber by means of passage 44, chamber 45, and idle tube 46. The idle tube communicates with

30 the chamber 45 by means of port 47, which is slightly above the fuel level in the constant level chamber, and a conventional idle adjusting screw

48 is also provided. A metering rod connected to the rocker-arm 18 controls the admission of fuel to the passage 44, as indicated in Figure 1.

35 In the device shown in Figure 5, the valve 35 is omitted, the pump capacity is slightly increased, and the passages 36 or 37 made so small as to constitute a high restriction to the flow of fuel, while permitting the admission of sufficient air to

40 relieve the suction at 28 and 29, at least to such an extent as to prevent the withdrawal of fuel from the float chamber through the pump pas-

38 sages.

45 The operation of the device is as follows:

For constant speed operation, the carburetor operates in the conventional manner, the proper amount of fuel being applied by the idle port 43, and the main nozzle 42, either separately or together, according to the speed at which the carburetor is operated. Whenever the throttle 6 is opened the piston 23 descends into cylinder 22

50 and discharges fuel through outlet check valve 26 and passageways 27 and 28. The pressure existing in the passageway 28, of course, tends to cause a discharge of fuel through passages 36 and 37 into

55 passage 39 which leads back to the constant level chamber, but the fibre valve 40, being made extremely light, seats against the shoulder or valve seat 35 with the first upward movement of gasoline, thereby preventing any substantial flow of

60 gasoline into the passageway 36 and communicating passageways.

As soon as the pressure in the passage 27 is relieved by discharge through passageway 28, the valve 40 drops down to its lower position indicated in Figure 3. In case the valve should be inclined

65 to stick to its seat due to the surface tension of the gasoline, the suction applied at the discharge outlet of the nozzle 28 will pull the valve downwardly and unseat it.

When the carburetor is operated at high speed, that is to say when a very large amount of air

70 is flowing through the mixing conduit, developing substantial suction therein, there will be a

constant flow of air through the passageway 39 into passageways 37, 36, and 34, thereby substantially relieving the suction at the junction 29 of passageways 27 and 28, so that no gasoline will be withdrawn by suction from the constant level chamber through the pump. In case the valve 35 should fail to operate properly, the leakage will return to the float chamber through the passage 39, so that no fuel will be spilled on the outside of the carburetor.

80 It will be understood that in the construction of the inlet and discharge valve for the accelerating pump these valves and their springs if any are made as light as possible and arranged to open under extremely low pressures. Frequently

90 ordinary ball check valves, mounted in vertical passages, seated by gravity only, are used and it will be understood that with such valves very little suction would be required to draw gasoline through the pump to the pump discharge nozzle.

95 With this construction, however, even a very small bleed of air through passages 39, 37 and 36 is sufficient to relieve the suction so that no fuel will be discharged through the pump nozzle except when the pump is operated.

100 It will be understood that in the construction of the inlet and discharge valve for the accelerating pump these valves and their springs if any are made as light as possible and arranged to open under extremely low pressures. Frequently

105 ordinary ball check valves, mounted in vertical passages, seated by gravity only, are used and it will be understood that with such valves very little suction would be required to draw gasoline through the pump to the pump discharge nozzle.

110 With this construction, however, even a very small bleed of air through passages 39, 37 and 36 is sufficient to relieve the suction so that no fuel will be discharged through the pump nozzle except when the pump is operated.

115 It will be understood that in the construction of the inlet and discharge valve for the accelerating pump these valves and their springs if any are made as light as possible and arranged to open under extremely low pressures. Frequently

120 ordinary ball check valves, mounted in vertical passages, seated by gravity only, are used and it will be understood that with such valves very little suction would be required to draw gasoline through the pump to the pump discharge nozzle.

125 It will be understood that in the construction of the inlet and discharge valve for the accelerating pump these valves and their springs if any are made as light as possible and arranged to open under extremely low pressures. Frequently

130 ordinary ball check valves, mounted in vertical passages, seated by gravity only, are used and it will be understood that with such valves very little suction would be required to draw gasoline through the pump to the pump discharge nozzle.

135 It will be understood that in the construction of the inlet and discharge valve for the accelerating pump these valves and their springs if any are made as light as possible and arranged to open under extremely low pressures. Frequently

140 ordinary ball check valves, mounted in vertical passages, seated by gravity only, are used and it will be understood that with such valves very little suction would be required to draw gasoline through the pump to the pump discharge nozzle.

145 It will be understood that in the construction of the inlet and discharge valve for the accelerating pump these valves and their springs if any are made as light as possible and arranged to open under extremely low pressures. Frequently

150 ordinary ball check valves, mounted in vertical passages, seated by gravity only, are used and it will be understood that with such valves very little suction would be required to draw gasoline through the pump to the pump discharge nozzle.

155 It will be understood that in the construction of the inlet and discharge valve for the accelerating pump these valves and their springs if any are made as light as possible and arranged to open under extremely low pressures. Frequently

160 ordinary ball check valves, mounted in vertical passages, seated by gravity only, are used and it will be understood that with such valves very little suction would be required to draw gasoline through the pump to the pump discharge nozzle.

165 It will be understood that in the construction of the inlet and discharge valve for the accelerating pump these valves and their springs if any are made as light as possible and arranged to open under extremely low pressures. Frequently

170 ordinary ball check valves, mounted in vertical passages, seated by gravity only, are used and it will be understood that with such valves very little suction would be required to draw gasoline through the pump to the pump discharge nozzle.

175 It will be understood that in the construction of the inlet and discharge valve for the accelerating pump these valves and their springs if any are made as light as possible and arranged to open under extremely low pressures. Frequently

- charge of fuel from said accelerating device into said vent passageway.
4. In a carburetor, means forming a mixing conduit, an accelerating pump, said pump having a discharge passageway leading into said mixing conduit, a valve controlled vent in said discharge passageway, said vent having a valve of light weight material adapted to be floated and moved to closed position by liquid fuel.
- 10 5. In a carburetor means forming a mixing conduit, said mixing conduit having a discharge outlet, a throttle valve controlling said discharge outlet, main fuel supply devices for supplying the normal requirements of fuel to said carburetor during constant speed operation, a constant level fuel chamber for supplying fuel to said main fuel supply device, a throttle operated accelerating pump also receiving fuel from said constant level chamber, said pump having a discharge passageway extending to a point substantially above the level of fuel in said constant level chamber, and having a discharge outlet in said mixing conduit, a vent at a point in said discharge passageway above the fuel level in said constant level chamber, a fibre valve controlling said vent and a passage connecting said vent with the upper part of the constant level chamber.
- 15 6. In a down draft carburetor of the plain tube type, a mixing conduit having a throttle controlled outlet, means including a venturi within said conduit and forming a zone of high suction anterior of said throttle, a main fuel supply device discharging at a point within said zone of high suction and delivering the proper amount of fuel to said mixing conduit during high speed operation, a constant level fuel supply chamber, an accelerating pump, a discharge conduit for said pump having a restricted outlet discharging into said mixing conduit at a point of low suction anterior to said venturi, a vent for said discharge conduit at a level substantially higher than the level of fuel in said constant level chamber and higher than the discharge outlet, and a valve for controlling said vent.
- 20 7. In a down draft carburetor of the plain tube type, a mixing conduit having a throttle controlled outlet, a venturi mounted within said conduit anterior to said throttle, a constant fuel supply chamber, an accelerating pump, a dis-
- charge conduit for said pump having a restricted outlet discharging into said mixing conduit at a point of low suction anterior to said venturi, a vent for said discharge conduit at a level substantially higher than the level of fuel in said constant level chamber and higher than the discharge outlet, and a valve for controlling said vent, said valve being of the flat plate type and being mounted in a plane at an acute angle to the horizontal whereby the tendency of said valve to be held in closed position by the surface tension of the fuel will be minimized.
- 25 8. In a carburetor, a mixing conduit having a restriction therein, said restriction forming a zone of high suction, a main fuel supply device discharging within said zone, an accelerating pump, a constant level fuel chamber supplying both said main fuel supply device and said accelerating pump, said accelerating pump having a discharge passageway extending upwardly to a point substantially higher than the level of fuel in said constant level chamber and having a valve controlled vent at said point, said discharge conduit extending downwardly a substantial distance from said vent and having an outlet within said mixing conduit in a zone of low suction anterior to said zone of high suction.
- 30 9. In a carburetor, a mixing conduit having a restriction therein, said restriction forming a zone of high suction, a main fuel supply device discharging within said zone, an accelerating pump, a constant level fuel chamber supplying both said main fuel supply device and said accelerating pump, said accelerating pump having a discharge passageway extending upwardly to a point substantially higher than the level of fuel in said constant level chamber and having a valve controlled vent at said point, said discharge conduit extending downwardly at an angle from said vent and having an outlet within said mixing conduit in a zone of low suction anterior to said zone of high suction, the valve for controlling said vent being of the flat plate type and being mounted in a plane at an acute angle to the horizontal, whereby the tendency of said valve to be held in closed position by the surface tension of the fuel will be minimized.
